KNITTING MACHINE

Vincent Lombardi, Garden City, N. Y., assignor to
Lombardi Knitting Machine Co., Inc., Brook-
lyn, N. Y., a corporation of New York

Application April 3, 1941, Serial No. 386,631

27 Claims. (Cl. 66—135)

This invention relates to knitting machines. An object of the invention is to provide an improved type of knitting machine whereby a plurality of yarns may be efficiently and effectively incorporated into a fabric in a desirable manner.

A further object is to provide improved knitting methods.

Other objects of the invention will in part be obvious and will in part appear hereinafter.

The invention accordingly comprises the features of construction, combinations of elements and arrangements of parts, all of which will be exemplified hereinafter and the scope of the application of which will be indicated in the claims.

For a fuller understanding of the nature and objects of the invention, reference should be had to the following detailed description taken in connection with the accompanying drawings, in which:

Fig. 1 is a plan view of one form of knitting machine embodying the invention;

Fig. 2 is a sectional view; Fig. 2a is a fragmentary sectional view along the line x—x of Fig. 1;

Fig. 3 is a larger-scale fragmentary view looking outwardly from within the yarn-guide supporting annulus and the top of the needle cylinder, with which a schematic showing is combined;

Fig. 4 is a fragmentary perspective view looking downwardly and inwardly at the yarn-guide operating mechanism;

Fig. 5 is a detail view of a control bracket adapted for use therein;

Fig. 6 is a top view of the yarn guide operating mechanism of Fig. 4;

Fig. 7 is a schematic showing illustrating one form of operation of the selective means and the yarn guides;

Fig. 8 is a perspective view looking outwardly at a portion of a modified form of machine;

Fig. 9 is a similar view showing another modification;

Fig. 10 is a diagrammatic view of a portion of the cam track;

Fig. 11 is a vertical sectional view showing further modifications;

Figs. 12a and 12b are fragmentary plan views of the machine of Fig. 11, there being included a diagrammatic view showing a type of needle operation;

Fig. 13 is a fragmentary vertical sectional view along the line 13—13 of Fig. 12a;

Fig. 14 is a similar view along the line 14—14 of Fig. 12b;

Fig. 15 is a perspective view of a yarn guide of the type shown in Figs. 11—14; and

Fig. 16 is a fragmentary top view illustrating the operations of the yarn guide of Figs. 11—15 in

an instance where this would pass between raised needles during its swing.

In my copending application Serial No. 254,580, filed February 4, 1939, Patent No. 2,231,673, issued February 11, 1941, there is exemplified a form of knitting machine wherein yarn is fed back and forth into position to be received by a limited number of needles. The present invention in certain of its aspects is directed to the provision of means whereby such operations may be simplified, the design capacity of the machine increased, the smoothness and certainty of operation under varying conditions improved, and supplemental operations effectively included; also to the provision of machines wherein yarn may be supplied to a group of needles of limited extent in a highly efficient, effective and satisfactory manner, and to the provision of machines, mechanisms and elements of a variety of improved characters. The present invention also contemplates the provision of improved knitting methods.

While the invention in certain of its more specific aspects is directed to the provision of improved types of circular knitting machines and is exemplified in connection with a circular knitting machine having a stationary needle cylinder, the invention in various of its broader aspects may be embodied in circular knitting machines of any well known type, including cylinder machines, dial machines, and cylinder-and-dial machines, and also, in certain instances, on flat knitting machines; and may also be embodied in machines wherein the needle bed is rotatable or otherwise movable and certain of the other parts stationary, or wherein the needle bed is stationary and wherein certain of the other parts revolve about or otherwise move along said bed.

The invention, moreover, while exemplified in connection with a latch-needle machine, is in many of its aspects, equally applicable to a spring-needle machine, or to a machine having other types of needles.

In the drawings, rotating parts are cross-hatched with the lines running from the lower left to the upper right, and the stationary parts are cross-hatched with the lines running from the upper left to the lower right.

The form of machine exemplified in Figs. 1 through 6 comprises a needle bed which, in the present instance, is in the form of a stationary needle bed in the form of a cylinder 5, having a series of vertical slots 6 in its outer surface. In each of suitable ones of these slots (of all of them in the present instance) there is disposed a latched needle 7 mounted for independent sliding movement in a direction lateral of the bed 5. Secured to the needle cylinder 5 is a sinker bed 8, in the slots 9 of which are disposed a series of sinkers 10 which are of conventional form and

which are operated by a rotating sinker cam ring 11, which is freely supported on the bed 8. The needles are operated by means carried by a rotating unit 12. From this unit there extends an adjustable arm 13 by means of which the sinker cam ring 11 is driven.

Carried from the rotatable unit 12 by posts 14 is a rotatable table or ring 15 having an inner ledge 16 which freely supports an annulus 17 which may be held stationary with respect to the cylinder 5, or may be moved independently of the rotatable unit 12, and which serves to carry a series of bobbins 17' and of limited-extent yarn-feeds 19. The annulus 17 is prevented from rotating with the rotatable unit by means of a gear arrangement comprising an annular gear 18 on the annulus 17 meshing with a pinion 19' fixed on a shaft 20 journaled in brackets 21 carried from the posts 14. Also fixed to the shaft 20 is a pinion 22 of the same size as pinion 19' and meshing with an annular gear 23 of the same size as gear 18 and formed on a ring 24 carrying brackets 25 which are adapted to be held stationary or shifted as desired by mechanism hereinafter to be described. The ring 24 is freely supported by an annulus 26 which is carried by the brackets 21 and which carries a bobbin-supporting unit 27 which rotates therewith. Yarn from each of a plurality of bobbins 28 on the unit 27 is conducted by suitable means to eyelets 29 and 30 inside the ring 26, thence to eyelets 31 and 32 fastened on brackets on ring 15 and thence thru an eyelet 33 to a main yarn feed 34, a plurality of which (eight in the present instance) are mounted on the sinker cam ring 11. It will be appreciated, however, that in certain instances the main yarn feeds may be omitted, and only the yarn-feeds 19 employed.

Each of the limited-extent yarn-feeds 19 consists of a member extending generally downwardly from an arm 35 and mounted for angular adjustment thereon by means of a set screw 35'. The arm 35 is mounted for rotary movement in a horizontal plane on an axis running substantially thru the line of the needles, by means of a hollow shaft 36 on which one end 37 of the arm 35 is secured, and which is journaled in the annulus 17 and may also, if desired, be journaled in an overlying annulus 39 supported from 17 by posts 40 serving to hold these annuli together. Each shaft 36 is formed with a supporting shoulder 42.

The needles are equipped with butts 43 and are adapted to be fully advanced by means of a cam 44 prior to the passage of each main yarn feed 34. Both the cams 44 and the main yarn feeds 34 are, in the present instance, removably mounted so as to be omitted or replaced as desired, and the other operating cams are likewise removably mounted. In order to select needles to be advanced for the incorporation of yarn from the feeds 19, there is provided in association with some or all (all in the present instance) of the needles, individual needle jacks 45, swingable between an outer position as shown in Fig. 2 wherein their butts 46 will be engaged by a cam 47, and an inner position in which their butts will not be engaged by this cam. In order to move the jacks to an outer position, there is provided in advance of each cam 47 a cam 48 driven to rotate with the rotating unit 12; and in order to selectively move these jacks to an inner position between the times of passage of the cam 48 and of the cam 47, there is provided a selecting mechanism, including drums 49, and construct-

ed and operating in the manner disclosed in detail in my Patent No. 1,792,647, dated February 17, 1931 (the form illustrated in Figs. 1-13 of said patent being the form exemplified herein).

In order to retract the needles there are provided a plurality of cams 49', one of these cams being provided after each main yarn feed, and one being provided to retract the needles after a yarn from a feed 19 has been fed or might have been fed to needles advanced by the cam 47, pursuant to a selection by the selecting mechanism. The cam arrangement at the main yarn feeds is shown in Fig. 2, the cam arrangement at the points of yarn guide operation being shown in Fig. 2a. It is to be noted that, as shown, the cam 47 is of such height as only to raise the needles to a tucking position (so that, with suitable selection by the selecting mechanism, to cause, for example, every other needle, or every third or further spaced needle, or two out of three, two out of four, or three out of four needles, etc., to be partially advanced to receive yarn without casting, the needles will act to lay-in rather than knit the auxiliary yarn). All of the cams 44, as exemplified, are arranged to cause the main yarns to be knitted. However, by providing means (such, for example, as long and short butts on the needles and suitable cams at suitable points), desired ones of the main yarns may be laid in without departing from the invention in its broader aspects. In the present instance, there is provided a cam 47 and an associated retracting cam 49' between each of the main yarn feeds so that a main yarn feed will pass and the main yarn be knitted on the needles elevated by the cam 44 after each retraction of the needles subsequent to an operation of a cam 47.

As above set forth, the brackets 25 are adapted either to be held stationary, in which case the annuli 17 and 39 will maintain their position with respect to the needle cylinder so that an individual yarn feed 19 will always encompass the same needles during its swing; or to be shifted, in which case the annuli 17 and 39 will be shifted thru the medium of the gearing 18-23 so as to permit the swing of a yarn feed 19 to encompass different needles at different times. Due to the operation of this means, diagonal and other varying designs may be effectively incorporated in the fabric produced. Various means may be utilized to effectuate such shifting, the particular means exemplified being that disclosed in my Patent No. 2,231,673, issued February 11, 1941, and comprising an annulus 408 from which the brackets 25 extend inwardly, and which is formed with external gear 409 meshing with a pinion 410 fixed to a shaft 411 which is journaled in the bracket 86 and which has fixed thereto a gear 412 meshing with a small gear 413 carrying a large gear 414 which meshes with a worm 415 on a shaft 416 carrying a pair of ratchet wheels 417 and 418, the teeth of which are disposed in opposite directions as indicated in Fig. 2. A pawl 419 is provided in association with the wheel 417, and an oppositely directed pawl 420 is provided in connection with the ratchet wheel 418. The pawls 419 and 420 are each fixedly secured on a rod 421 which is mounted, in a manner hereinafter described, for rotative movement pursuant to the positioning of a link 422 which is pivotally connected at 423 to a link 424 which in turn is pivotally connected at 425 to an operating arm 426 which is pivoted at 427. The link 424 is composed of two telescoping members non-separably connected in a telescoping manner

and normally held in extended relationship by a spring 428 against the pressure of which the pawls may be lifted as they slide over the teeth. The arm 426 is normally swung in a counter-clockwise direction, Fig. 2, by means of a spring 429 and is adapted to be swung in a clockwise direction by projections on a pattern chain 430. The pattern-chain sprocket 436 is rotated relatively slowly when compared with the linear speed of rotation of the unit 12 by suitable means a number of which are known to the art.

The arm 426 is formed with a nub 431 having a cam surface 438 of such nature that the arm will be lifted as a projection on the pattern chain 430 moves under the nub 431. The pattern chain carries high projections 439 adapted to move the arm 426 to the position shown in dotted lines and low projections 440 adapted to move the arm 426 to the position shown in dot-and-dash lines. It will be noted that both types of projection are made of varying extent longitudinally of the chain so that they will be effective for greater or lesser periods when the chain is moving normally.

The rod 421 is rotatably carried on one end of a lever 441, which is rotatably mounted on the shaft 416. This lever is given an oscillating movement by means of an eccentric 442, the yoke 443 of which is freely connected to the other end of the lever 441 at 444. The eccentric 442 is keyed to a shaft 445 which is rotated from the rotating unit 12 by means of gearing 446. The lever 441 will accordingly be given an oscillating movement. If the rod 421 is in the position shown in dot-and-dash lines, the ratchet wheels 417 and 418 will not be effected by the oscillation of the lever 441. When, however, the rod 421 is in the position shown in dotted lines, the pawl 420 will act against the teeth of the ratchet wheel 418 to advance the wheel one tooth in a clockwise direction for each rotation of the shaft 445; and when the rod 421 is in the position of Fig. 2, the pawl 419 will act to advance the ratchet wheel 417 in a counter-clockwise direction one tooth for each rotation of the shaft 445.

Each shaft 36 carries on its upper end a pinion 50, and in order to rotate each yarn guide 19 there is provided in the present instance a swingable bracket 51 carrying an interior arcuate gear 52 meshing with the gear 50, and a swingable bracket 53 carrying an external arcuate gear 54 meshing with the pinion 50. The brackets 51 and 53 are rotatably mounted on a post 55 carried on the stationary annulus 17. As will be seen, when the bracket 51 is swung in a counter-clockwise direction (Fig. 4), the pinion 50 and the yarn guide 19 will be rotated in a counter-clockwise direction and the bracket 53 will be swung in a clockwise direction. Conversely, when the bracket 53 is swung in a counter-clockwise direction, the pinion 50 and the yarn guide 19 will be rotated in a clockwise direction and the bracket 51 swung in a clockwise direction. In order that swinging movements may be imparted to the swingable brackets 51 and 53, each of them carries an actuating arm adapted to extend into the path of movement of cams which are mounted on a rotatable table 15, and in order that different ones of the brackets 51 and different ones of the brackets 53 may be selectively operated, different ones of these brackets carry arm portions in different positions. In the present instance, each bracket 51 carries an operating arm 56 adapted to project into the path of cam movement when this

bracket has been swung in a clockwise direction, and each bracket 53 carries an operating arm 57 adapted to project into a path of cam movement when this bracket has been swung in a clockwise direction. Each arm 56 and each arm 57 has its outer portion so formed that it will be solid in certain of four vertically spaced positions and will be cut away in the certain other of said positions. For example, in Fig. 4 the arm 56 of the left-hand one of the two brackets illustrated is shown solid in the uppermost position and cut away in the three lowermost positions, and the arm 57 thereof is shown cut away in the two uppermost positions and in the lowermost position and solid in the remaining position; and the arm 56 of the right-hand one of the two brackets illustrated is cut away in its uppermost and two lowermost positions and solid in the remaining position, and the arm 57 is cut away in the two uppermost positions and the lowermost position, and solid in the remaining position. While each of these arms is shown as solid in only one of the four positions, both or either of them may be solid in two, three or all four of the positions, depending upon the action desired by the particular yarn guide 19 controlled thereby.

For the operation of the swinging brackets 51 and 53 through the medium of their arms 56 and 57, respectively, in a selective manner, there are provided at suitable points on the rotating table 15 a series of sets of four cams 58 adapted to be selectively positioned so as to contact an outer portion of the arm 56 in one or another of the four positions in which these outer portions may be solid, and a series of sets of four cams 59 adapted to be selectively positioned to contact an outer portion of the arm 57 in one or another of the four positions in which these outer portions may be solid. Each set of cams is removably positioned at a point such that its operation will not interfere with the operation of any of the main yarn feeds. In order to provide for the movement of the yarn guides 19, as hereinafter to be described, each of the cams 58 and 59 is adapted to be placed in any one of three positions: (1) an innermost position in which it will impart a full swinging movement to a swingable bracket; (2) an intermediate position in which it will impart a partial swinging movement to a swingable bracket; and (3) an outermost position in which it will not contact a swingable bracket. In order that the swingable bracket and the pinion and yarn guide will remain in a position into which it is swung or rotated, each bracket 51 is formed with three notches 60, and there is carried by the annulus 17 a spring 61 adapted to bear against the outer surface of the bracket 51 and to seat in any notch 60 which is juxtaposed with its outer end.

Each of the cams 58 and 59 is formed with a pair of slots 62 and 63, which are respectively adapted to slide past small-diameter portions of posts 64 and 65 carried by the rotatable table 15, and each of these cams is also formed with a notch 66 in which there is set a head 67 on a lever 68 centrally pivoted on a post 69 on the table 15. Each head 67 is urged outwardly by a spring 70 extending from its lever on the same side of the post 69 as the head 67, and on the other side of the post 69 the lever is formed with a portion 71 adapted to be urged outwardly so as to swing the head inwardly by a nub 72 on a disk 73 removably mounted on a post 74 carried on the table 15. The disks 73 are interchangeable

and displaceable, and each carries one or more suitably disposed nubs. After the discs have been suitably assembled on the post 14 they are keyed with a ratchet 75 which is adapted to be moved forward one notch by a pawl 76 at suitable times in the operation in accordance with setting mechanism hereinafter to be described. A plurality of sets of cams 58 and 59 are provided, the arrangement of discs 13 on the different posts 14 being similar or different depending on the operation desired. Certain of the nubs 72 will be short nubs and certain of the nubs will be long nubs. When a long nub is in contact with an end 11 of a lever 68, the corresponding cam 58 or 59 will be thrust to an innermost position. When a short nub is in contact with an end 11, the corresponding cam will be thrust inwardly to its intermediate position, and when no nub is in contact with the end 11, the corresponding cam will be held outwardly by a spring 10. It will thus be seen that by suitable arrangement of the disks 13 and by suitable positioning of the solid portions of the arms 56 and 57, a wide range of selective action may be had. It is to be noted that the swingable brackets 51 and 53 are removably secured on the posts 55 by means of screw bolts 17 so that these may be readily replaced by similar elements having arms with solid portions differently positioned.

Each pawl 76 is spring-pressed against its ratchet 75 and is pivotally supported from a horizontal rod 78 mounted for longitudinal sliding movement in a guideway 79 secured to a bracket on ring 15. Each rod 78 is provided with a spring 80 tending to move it outwardly and with a shoulder 81 to limit its outward movement. The outer end of each rod extends outwardly of its bracket so as to permit the same to be thrust inwardly on contact with a cam 82, which is mounted for vertical sliding movement between an upper position in which it will thrust the rod inwardly sufficiently to advance the ratchet one notch, and a lower position in which it will not contact the rod, the cam 82 being carried on a square rod 83 mounted for vertical movement in plates 84 and 85 secured to a fixed bracket 86. The rod is formed with a shoulder 87 which is adapted to ride on one end of a bell crank lever 88 from the other end of which there extends a link 89 to one end of a second bell crank lever 90 carrying at its other end a link 91 adapted to be actuated by nubs 92 on a pattern chain 41, driven by suitable means including gearing 41' in the manner well known in the art.

As will be seen, when a nub 92 lifts the lower end of the link 91, the inner end of the bell crank 88 will be elevated so as to move the cam 82 into the path of movement of the outer ends of the rods 78. When, on the other hand, there is no nub 92 beneath the link 91, the cam 82 will be in the position shown, and the rods 78 will be held outwardly by their springs so that the ratchets 75 will not be operated and the nubs 72 will remain in position to permit production of the patterns throughout a desired number of rotations of the machine.

The relative number of the active teeth on the gears 52 and 54 with respect to the number of teeth on the pinion 50 is such that when either of the swingable elements 51 or 53 is swung to its full extent, the pinion 50 and the yarn guide 19 will complete two rotations and when either of the swingable elements 51 or 53 is swung to one-half its extent, the pinion 50 and the yarn guide 19 will complete a single rotation.

It is to be observed that while in the exemplified construction the short nubs on the disc 13 are of such extent and the central notching 60 on the swingable element 51 is so placed as to provide for a complete rotation of the pinion 50 and the yarn guide 19 when a cam 58 operates from an intermediate position, that it is not necessary in most instances that the yarn guide 19 make a complete rotation; it being merely necessary that it move in an arc sufficiently greater than a semi-circle so that it will swing from a point behind the line of needles and return to a point behind the line of needles at the end of its swing. It is to be noted that the axis of each yarn guide 19 is at the rear of the line of the needles.

The yarn guides 19 are each adapted to be in an innermost position at the rear of the needle bed when at rest (i. e., when the springs 61 contact any one of the notches 60); and to swing circularly from this position behind the line of the needles and outwardly, thence in front of the line of needles still outwardly, thence in front of the line of needles while moving inwardly, and thence behind the line of needles when moving inwardly. Accordingly, when certain needles are elevated inside a circle described by the yarn guide in its movement, yarn will be drawn in front of these needles then against them and about them, so that the yarn will be fed to the needles. If the yarn guide makes one rotation, a single length of auxiliary yarn will be fed to the needles, and if the yarn guide completes two rotations while the needles are elevated, a double length of auxiliary yarn will be fed to them.

The yarn guides 19, as exemplified, are shown as mounted and as adjusted so as to encompass slightly over 30 needles. It will be appreciated, however, that the adjustment may be varied to encompass a limited but varying number of needles. In certain instances, machines embodying the invention may be provided with yarn guides having a swing encompassing from 60 to 120 or more needles depending on the closeness of the needles, the arrangement of the various operating parts, the size of the machine, and other factors.

It is to be noted that, so long as the auxiliary yarn is fastened into the fabric before a rotation of the yarn guide, the feeding action will be performed regardless of the direction of rotation of the yarn guide. Thus with the mechanism shown, if the parts are in a position such that the end of spring 61 engages the central notch 60, the action either of a cam 58 (when in an intermediate position) on a solid portion of an arm 56 or the action of a cam 59 (when in an intermediate position) on a solid portion of an arm 57 will serve to impart to a yarn guide 19 a single rotation which will feed yarns to needles elevated within the circle of movement of the yarn guide. Likewise, after a bracket 51 has been swung from the position in Fig. 4 through its full length to impart a double rotation to the yarn guide, and the needles operated to incorporate into the fabric the double strand of yarn thus fed, and certain needles elevated again, a full swinging movement of the associated element 53 will operate the yarn guide 19 to feed a double strand of yarn to the needles while swinging in the other direction. It will be observed that when the yarn guide is swung through a double rotation, there will be uncaught lengths of yarn at the rear of the fabric. The presence of such lengths may be desirable where these are drawn tight to provide puckles or bulges

in the fabric, the yarn-tensioning means, shown at 38, being made particularly strong when this is desired. In instances where the presence of uncaught lengths of yarn is undesirable, however, the exemplified mechanism permits all the yarn fed from a yarn guide to be fed to the needles by merely having a suitable cam 58 in an intermediate position so that the element 51 will be swung half way, and after the yarn thus fed has been incorporated into the fabric by having a suitable cam 59 in an intermediate position so as to effectuate the return of the yarn guide to again perform a feeding operation while suitable ones of the needles are in position to receive said yarn.

At the bottom of Fig. 3 there are illustrated schematically the resultants of a series of yarn-guide movements, these being shown with respect to each of the three yarn guides illustrated in the figure. In the three lower courses 93, 94, and 95, no needles except, for example, the outer two of three or four central ones will have been partially advanced for reception of yarn from the yarn guide, and yarn from each yarn guide will have been fed by a movement of each of the yarn guides to the right as it passes in front of the needles in course 93, by a movement of each yarn guide to the left as it passes in front of the needles in course 94, and by the movement of each yarn guide to the right as it passes in front of the needles in course 95. In course 96 alternate or otherwise spaced needles of a group of about thirty needles will have been partially advanced for the reception of yarn during a swinging movement of the central yarn guide 19 to the left as it passes in front of the needles, the left and right yarn guides being unselected in this course. In course 97 suitably spaced needles of a group of about thirty needles, including at least one needle overlapping with the needles partially advanced in course 96 will be raised to partially advanced position for reception of the yarn during swinging movement of each of the left and right yarn guides to the left as they pass in front of the needles. The central yarn guide 19 is unselected during this period. In course 98 the operations of course 96 are repeated except that the central yarn guide passes to the right in front of the needles, and in course 99 the operations of course 97 are repeated except that the outer yarn guides pass to the right.

It will be appreciated that a wide number of different types of designs may be incorporated in a fabric by suitable selections of the needles and of the yarn guides, and that design yarns may be thereby suitably incorporated in a fabric composed mainly of weft yarn either by being laid in, by being knitted in along with the weft yarn, by being knitted in place of certain loops of the weft yarn, by being caught in at certain points and floated between them, or by being arranged with a weft yarn in other manners. Likewise, various types of fabric may be formed of the design yarn alone.

Besides various designs such as polka dots, circles, squares, diamonds and the like, various more complicated designs may be obtained and striped effects may be produced. Diagonal striping may be effectuated either by an operation of the shifting mechanism acting through the means including the gear 408 and the brackets 25 or by an overlapping of design portions formed by adjacent yarn guides.

There is exemplified schematically in Fig. 7 one form of operation of a machine, such as illustrated in Figs. 1-6, whereby a plaid design is

formed. In this type of operation, alternate yarn guides are operated in alternate courses and the variability of the design is governed entirely by the needle control. While only a single swing of each yarn guide operated is exemplified, it will be appreciated that all or some of the yarn guides may be given a double swing whenever desired. It is also to be noted that while the machine is arranged for the catching-in of the yarn from the yarn guides without forming loops of the same, the invention in its broader aspects is readily adapted for the knitting of yarn into loops, it being only necessary to employ higher cams 47 for this purpose. In the exemplified operation, it is contemplated that a main yarn feed will pass, and loops of the yarn therefrom be formed, at each course indicated, the operation occurring between successive yarn-guide operations.

In Fig. 7, the arcuate lines *a* through *j* indicate the catching of the yarn on the needles in successive courses of yarn-guide operation, and the arcuate lines *a'* to *j'* indicate the needle selection which results in such operation. Where one of these lines is shown extending outwardly away from the center of the arc, i. e., upwardly or leftwardly, it indicates that alternate needles are selected throughout such span. When a portion of the line is in a downward or rightward position it indicates that no needles are selected. The circles represent the overlapping swing of yarn guides L through T. It will be seen that in courses *a* and *c* alternate ones of thirty-two needles are selected for reception of yarn from yarn guides L, N, P, and R; and the remaining twenty-eight of a group of sixty needles left unselected. A similar selection occurs in course *b*, except that alternate needles are advanced for reception of yarn from guides M, O, Q, and S; and it is the middle twenty-eight of the thirty-two needles from which alternate ones were selected in course *a* which are now left unselected. The result is that groups of sixteen individually spaced needles are elevated in each course with the end needles of the group in successive courses overlapping. In the formation of course *a*, yarn guides L, N, P, and R, are swung so as to draw out yarn so that it will extend from left to right. In course *c* the same yarn guides are swung so as to draw out yarn from right to left. In the formation of course *b*, the yarn guides M, O, Q, and S are swung so as to draw out yarn from right to left. The yarn guide operations are repeated in succeeding courses, but it is to be noted that in courses *d* and *f* it is only two spaced needles, disposed at the left of the group intercepted by the swing of yarn guides M, O, Q, and S, which are raised, whereas in courses *e* and *g* it is only two spaced needles, disposed at the left of the group intercepted by the swing of yarn guides L, N, P, and R, which are raised. In courses *d* and *e* the yarn guides operated are swung to draw out yarn from left to right. In courses *f* and *g* the yarn guides operated are swung to draw out yarn from right to left. In the formation of course *h*, the same groups of sixteen needles raised in course *b* are again raised, and the yarn guides M, O, Q, and S are swung to draw out yarn from left to right to feed it to these needles. In courses *i* and *j* the operations in the formation of courses *a* and *b* are repeated.

As will be seen (Fig. 2), yarn from each of certain of the bobbins 47 is carried thru suitable eyelets and over the yarn-tensioning mechanism 38 to the interior of the hollow shaft 36 and

thence to the yarn guide 19. The interior diameter of the hollow shaft 36 is made large enough to accommodate an extra yarn which can run directly from the lower end of the shaft to the fabric and so that yarn guided by the guide 19 ¹⁵ may wrap around the extra yarn.

In the form of construction shown in Figs. 1-6 such an extra yarn may run from certain of the bobbins 17' to the hollow shaft 36. No such yarn is shown in the machine as illustrated, but the ¹⁰ manner of its use will be readily apparent from the exemplification in connection with Fig. 8. In this figure there is shown a form of machine generally similar to the form of Figs. 1-6 except that it is considerably simplified. The shaft 36a ¹⁵ on which the yarn guide 19a is mounted has near its upper end a pinion 50a with which there meshes a gear 100 carrying a pinion 101 with which a gear 102 carried on a bracket 103 meshes. The bracket 103 carries a portion 57a similar to ²⁰ the portion 57 of the bracket 53 and operated by a set of four cams 59a similar to the cams 59 and operated by discs 73a formed, mounted, arranged and controlled similarly to the discs 73, but having only long nubs, in the present instance. In the present exemplification the action of cams 59a on the operating arm 57a of the bracket 103 is opposed by a spring 104 so that as soon as the operating arm is freed by its cam it will immediately return to normal position. Thus any swinging movement of the yarn guide 19a resulting from an operation of a cam 59a will be immediately followed by similar swinging movement of the yarn guide 19a in the opposite direction. The general arrangement of the machine and the elements thereof will be readily understood in connection with the description of the machine exemplified in Figs. 1-6, it being noted that similar elements in Fig. 8 are designated by similar reference numerals with the addition of the subscript *a*.

As will be seen a yarn 105 extends through the hollow post 36a to the yarn guide 19a. An extra yarn 106 also extends through the hollow shaft 36a. This does not extend to any yarn guide but extends to the rear of the fabric and may be held thereagainst by the yarn 105. As will be seen, each time the bracket 103 is operated by a cam 59a, the hollow shaft 36a will be rotated. The exemplified gearing is such that substantially two rotations will be imparted to the tube 36a due to an operation of a cam 59a. A double rotation in the opposite direction results from the action of the spring 104. This double rotation results in swinging the yarn guide 19a twice around the yarn 106 so that the yarn 105 is wrapped about the yarn 106 as indicated at 107. If the yarn 105 is caught by the needles and incorporated in the fabric intermediate successive portions 107, it will, as will be seen, hold the yarn 106 firmly against the rear of the fabric. In the present instance, certain spaced needles as indicated at 108 are partially advanced by the operation of selective means such as exemplified in connection with Figs. 1-7 to partially advance the selected needles indicated at 108 to a position in which they will receive yarn without casting, this operation taking place before the operation of a cam 59a. The operation of the cam 59a then causes the yarn guide 19a to be swung to wrap the yarn around the needles, as shown. The retraction of these needles occurs during the time when a cam 59a holds the arm 57a inwardly. Thereupon, when the arm 57a is released from the cam 59a, the spring 104 will

act upon the bracket 103 to impart to the hollow shaft 36a a double rotation in the opposite direction. During this double rotation the yarn 105 will be wrapped around the yarn 106. The yarn 106 can be an elastic yarn, or yarn of some other character or color differing from the character or color of the yarn 105 of which the body of the fabric is composed, or from the character or color of the yarn 105. For example, the yarn 109 may be white woolen yarn, the yarn 105 black woolen yarn, and the yarn 106 elastic yarn, such as a rubber strand, or a rubber-treated fibrous yarn; the yarns 109, 105 and 106 may all be rayon yarns, but the yarn 106 a particularly thick form of yarn; the yarn 109 may be red rayon yarn, the yarn 105 blue rayon yarn and the yarn 106 white cotton yarn; etc.

In Figs. 9 and 10, there is illustrated a modified form of limited-extent yarn-feeding means and operating means therefor adapted for use in a variety of types of machines, but particularly adapted for use in a machine having needles, needle-manipulating means, main yarn feeds and other elements not illustrated, all generally similar to those illustrated in the form of construction exemplified in connection with Figs. 1 through 6. As exemplified in Figs. 9 and 10, there is provided a stationary bed 200 serving to support a suitable number of limited-extent yarn feeding means generally indicated at 202. Each such means comprises a pair of coaxial independently-rotatable tubular members 203 and 204; a tubular member 204 being fitted within each tubular member 203. Within each tubular member 204 are two small tubes 205 and 206 through which individual yarns from bobbins such as the bobbins 17', are adapted to extend. From the lower end of the tube 205 a yarn extends to an eyelet 207 in a yarn-guiding element 208 carried on the tube 203; and from the lower end of tube 206 a yarn extends to an eyelet 209 in a yarn-guiding element 210 mounted on the lower end of tubular member 204. It is to be noted that the yarn-guiding elements 208 and 210 are adjustably mounted by means of set screws 211 and 212, so that the distance of the individual eyelets 207 and 209 from the axis of the tubular members 203 and 204 may be individually adjusted. As will be seen, the yarn-guiding element 210 is disposed sufficiently beneath the course of the yarn from the tube 205 to the eyelet 207 so that it may be swung entirely independently of the yarn-guiding element 208.

In this manner different colors or characters of yarn may be suitably interspersed in a fabric. For example, if a red yarn extends through the eyelet 207, this yarn may be incorporated in a number of courses of the fabric by suitable rotative movements of the tubular member 203 and suitable needle manipulation, and thereafter the blue yarn extending to the eyelet 209 may be incorporated in a number of courses by suitable rotative movements of the tubular member 204 and suitable needle manipulation. It is also possible to closely intersperse the yarns as, by feeding one extent of red yarn to all or certain of the needles of a group, and, after this is incorporated in the fabric, to feed a blue yarn to all or certain of the needles of this group. Again, when desired, red and blue yarns for example may be fed together by swinging both yarn guiding elements 208 and 210 between the time when certain needles are advanced and when they are retracted. In addition, by adjusting one of the yarn-guiding elements 208 and 210 so that it will have a

swing of small radius and by adjusting the other so as to have a swing of large radius, two yarns may be fed together so that there may be a wide red design, for example, with a narrow blue design interspersed therewith. Numerous other design possibilities inherent in a construction of the character exemplified will be apparent. It is to be noted that as shown, the eyelet 207 is at a greater distance than the eyelet 209 from their common axis.

In Figs. 9 and 10, there is also exemplified an alternate form of operating means for the auxiliary yarn-feeding means, this being particularly exemplified as adapted to operate an auxiliary yarn-feeding means of the character indicated at 202, but being of a character adapted to provide for certainty and effectiveness of operation regardless of whether dual or single yarn-feeding means are employed and regardless of the particular character of the yarn-feeding means. On the upper end of each tubular member 203 there is formed a gear 215 which meshes with a rack 216 carried on a slidable element 217 mounted in a slot in bed 200 for radial sliding movement; and at the top of the tubular member 204 at the point above the gear 215 there is formed a gear 218 meshing with a rack 219 carried on a slidable element 220 mounted for radial sliding movement in a slot in the bed 200. Each of the slidable elements 217 and 220 carries on a rear portion thereof a rocker element 221 pivotally connected therewith at 221' and having at its forward end a portion 222 which may be swung upwardly out of the slot into a position to be engaged by any one of a plurality of cams 223 carried by a rotatable annulus 224 to move the rocker and its accompanying slidable element outwardly.

Each of the slidable elements 217 and 220 carries a butt 225 adapted to fit into a groove 226 in the rotatable annulus 224. Diverging from the groove 226 at each point where a cam 223 is operative is a branch groove 227 into which the butt 225 on a slidable element 217 or 220, as the case may be, may be moved whenever it, having been selected, is moved outwardly by the cam 223 (see Fig. 10). At a suitable later point the groove 227 is curved inwardly as indicated at 229 so as to merge with the groove 226 at 230, thus aligning all of the butts 225. It will be noted that as long as the butt 225 of a slidable element remains in the inner groove 226, the slidable element will impart no movement to the tube 203 or the tube 204, as the case may be; but as soon as a rocker 221 is selected and engaged by the cam 223 movement of one of the tubular members 203 or 204 in one direction will be caused, and when the butt 225 reaches the groove portion 229 a movement of the slidable element in the opposite direction will automatically be caused. Accordingly in this instance a two-directional yarn-feeding movement of the eyelet 207, or the eyelet 209, as the case may be, will result.

In order to select suitable ones of the slidable elements 217 and 220, each of some or all of the rockers 221 is provided at its rearward portion with one or more teeth 231 suitably disposed in one or more of four positions. These teeth, when the rearward portions of the rockers are elevated (by the action of a cam 241 carried by the annulus 224 and serving to press the forward portion 222 of the rockers downwardly), are adapted to project into a groove 233 in the bed 200. In order to selectively act upon the teeth to swing suitable ones of the rockers so as to permit the cam 223 to push such rockers and their accompanying slid-

able elements rearwardly, there is carried on the annulus 224 a suitable member of selective means comprising four selector cams 234 pivotally mounted at their forward ends and normally urged upwardly by springs 235 and adapted to be pressed downwardly in a selective manner by pins 236 removably disposed in selected ones of holes 237 in a rotatable drum 238. Thus, when a cam 234 has been pressed downwardly into the groove 233 by a pin 236, it will contact a tooth 231 on a slidable element, provided there is such a tooth in the path of travel of this cam on the particular rocker to swing the rocker; but when a cam is not depressed by a pin 236 a rocker will not be swung even though it has a tooth in a position aligned with this cam. It will be seen that the drum is formed with a series of sets of four holes 237 throughout its periphery, and that successive ones of these sets may be brought into a position in which any pins therein will contact the upper surface of the cams 234 to depress them when the drum is rotated step by step. In order to accomplish this step-by-step movement, the drum is provided with a ratchet 240 engaged by a pawl on a lever 241 which is operated by means hereinafter exemplified. A cam 241' restores the rockers prior to selection.

In the present instance, the bed 200 is mounted on an annulus 242 which is freely supported on a rotating annulus 243 which is mounted on posts 244 corresponding to the posts 14, and which carries an annular bracket 245 which in turn carries the annulus 224. The annulus 243 is freely supported on a stationary annulus 246 carried by vertical supports 247. The annuli 242 and 246 carry internal annular gears 248 and 249, with both of which a plurality of gears 250 carried by the rotating annulus 243 mesh, thus serving to hold the annulus 242 and the bed 200 stationary. The rotating annulus 243 is provided with bores 251 through which main yarns as from bobbins corresponding to the bobbins 28 may be conducted to main yarn feeds corresponding to the main yarn feeds 34. It will be appreciated, however, that the main yarn feeds may be omitted in certain instances, or, if provided, some or all of them may be left without yarn in certain cases.

The lever 241 is suitably mounted on one end of a rod 252 rotatably carried by an element 253 on the annulus 245, so that a partial rotation of the rod 252 will cause a single-step advancement of the drum 238. Fixed on the other end of the rod 252 is an arm 254, the free end of which traverses a path into which an abutment 255 carried in a stationary mounting may be moved at certain times in accordance with the operation of a pattern chain in a manner well known in the art.

It is to be noted that the yarn-guiding element 210 is adjustably mounted by means including a set screw 212, and comprises a member 257 in which the eyelet 209 is formed. The member 257 is specially formed so as to provide a long curved lower surface in order to assure that when this crosses a yarn extending to the eyelet 207 in the yarn guide 208 it will slide over this yarn and assure against tangling of this yarn with its own yarn. The eyelet 109, as will be seen, is formed in a projection on the outside of the member 257 and is in the form of a vertical bore, the yarn entering the upper portion of this bore as it comes from the tube, and leaving the eyelet at the bottom of the bore to further assure against tangling. The yarn guide 208 is adjustably mounted by means including a set screw 211, and the member 259, which extends downwardly a suit-

able distance and has the eyelet 207 formed on its lower end, also includes a bulging portion 260 over which its yarn extends after passing through a supplemental eyelet 261, whereby yarn tangling is further guarded against.

In Figs. 11-15 there is disclosed an arrangement generally similar to that of Figs. 9 and 10 but with various modifications. The yarn guides, which are spaced so that their swings overlap, are single instead of dual; the needles are advanced to engaging position for reception of yarn from the yarn guides; means are provided for preventing yarn from the yarn guides catching beneath the latches when the yarn therefrom is fed to the needles; and means are provided for providing slack in the yarn when it is fed to the needles by a swing of the yarn guide which passes in front of the needles in a direction opposite to the direction of movement of the cams. Other modifications are included as will be seen from the drawings and as indicated below. In the showing of Figs. 11-15, the parts not specifically referred to below, including those not shown, are generally similar to those of the exemplification of Figs. 9 and 10 (including parts shown in the exemplification of Figs. 1-6 which as above indicated are to be understood as included in the machine of Figs. 9 and 10); and bear reference numerals similar to those of corresponding parts in Figs. 9 and 10 with the addition of the subscript *b*, and where parts are shown not appearing in Figs. 9 and 10 but appearing in Figs. 1-6, similar parts bear reference numerals similar to those of corresponding parts in Figs. 1-6 with the addition of the subscript *b*.

In this form of construction, yarn-guiding members 210b are operated by means of slidable elements 220b carrying racks 219b which mesh with gears 218b on the top of tubular elements 204b. A yarn extends through each tubular element 204b—tubes corresponding to the tubes 205 and 206 of Fig. 10 being omitted.

The selected needles are fully advanced for reception of yarn from a yarn guide 210b at selected times when the same is to be swung. If desired, of course, the needles may be unadvanced at certain of such times and the yarn-guide swung without feeding, as, for example, when it is desired to swing it in one direction without action. At each point where the needles are to be fully advanced there is provided a cam 265 following a cam 47b and acting to further advance the needles to fully advanced position, these cams 265 being provided in the present instance, in advance of each cam 223b and in advance of each cam surface 229b. It is to be noted that the cam 223b and the cam surface 219b are further spaced than in the case of the machine of Figs. 9 and 10, this being due to the use of a drum selection in connection with the incorporation of the main yarn, as will appear herein-after. The selection in advance of each cam 265 will be such that all of the needles of certain groups will be selected at such points. It will be appreciated that the cams 265 may be disposed at some points and not at others and that the selection may be varied for making different ones of a variety of fabrics, but the particular selection indicated above is exemplified in Figs. 12a and 12b. In the present instance also, only two drums out of three are utilized for positioning the needles for reception of yarn during the swinging of the yarn guides and the third drum is utilized for the selection in advance of a main yarn feed. As particularly exemplified, more-

over, yarn is omitted from two out of three of the main yarn feeds shown, and the drums provide a selection such that spaced needles or groups of needles are selected and partially advanced by a cam 47b for inlaying the main yarn where it may be present. The selection of the slidable elements 220b carrying racks 219b is such, in the present instance, that alternate racks will be selected at a passage of one set of selecting means including a drum 338b and that the remaining racks will be selected at a passage of another set of selecting means including a drum 339b. The needle selection by those drums which select needles for reception of yarn during the swing of the yarn guides is such, and the needles advanced at certain operations of a given yarn guide are so chosen that one or more needles at the end of a group will be advanced at certain times and not advanced at other times so that the fabric will be securely tied together by an overlapping of certain of the successive series of knitted loops.

While, as exemplified in Figs. 11-15 the selection is such as to leave a clear space for the swing of the operated yarn guides beyond the ends of the groups of advanced needles, the yarn guides are so constructed as to facilitate their swing between needles in cases in which all, or a large number of, the needles are advanced as for example, in Fig. 16. This is desirable in instances when all the yarn guides are to be swung, or when two adjacent yarn guides are to be swung in immediate succession. This yarn guide construction is in the form of a vertical strip 266 (see Fig. 15) having a central vertical portion of only sufficient thickness so that a vertical bore 267 for conducting a yarn may be formed therein and with its outer portions tapering to sharp or narrow edges 268 and 269 which will easily enter the space between the needles and spread them, if necessary, to permit passage of the yarn guide therethrough. The yarn from the tube 204b enters the upper portion of the bore 267 through an opening 270 in an arm 271, the opening 270 being higher than the uppermost position of the needles.

There is exemplified in Figs. 12a and 12b one form of cam arrangement for giving the particular operation indicated above. The cams at P raise selected needles (in this case alternate ones of all the needles) to a partially advanced position for reception of yarn from the main yarn feed 34b shown in the upper portion of Fig. 12b and retract them. The cams at Q fully advance selected needles (all the needles of certain groups) for reception of yarn during the operation of alternate yarn guides 210b and retract them. The cams at R repeat the action at P, but since the main yarn feed at this point carries no yarn in the present instance, there is no yarn reception. The cams at S fully advance selected needles (all of the needles of the intermediate groups) for reception of yarn during the return operation (by the cam 229b) of the alternate yarn guides 210b operated at Q and retract these needles. At T the selection at P is again repeated but since the main yarn feed shown in the upper portion of Fig. 12a carries no yarn in the present instance, there is no yarn carried by this yarn feed in the exemplified arrangement.

In the exemplified operation the aforementioned "alternate" yarn guides feed to certain groups of needles an advance yarn which is knitted and then to the same groups a return

yarn which is knitted, and at a succeeding selection the "intermediate" yarn guides feed to the needles of intermediate groups an advance yarn which is knitted, and then a return yarn which is thereafter knitted. The "certain" and the "intermediate" groups together comprise all the needles of the series about the machine. As will be understood, parts of two rows of loops are thus first formed and then the parts between them are filled in, after which a main yarn is incorporated in the fabric by a laying-in operation. By provision of cams 265 at R and T, however, and the provision of yarns in the main yarn feeds at these points and a selection of the needles of the intermediate groups at these points, a main yarn may be used to fill in the gaps after each knitting, in response to a feeding by an "alternate" yarn feed, and by the similar provision of yarn and a similar selection at other main yarn feeds, the same result may be obtained after the operation of the "intermediate" yarn guides following a further selection, giving four rows of loops instead of two. In any case, however, it is desirable to have an overlap of certain of the parts of rows in certain courses to hold the fabric together. In the present instance, the selection of groups of needles is shifted five needles in one direction for the advance and return operations following a pair of yarn guide selections which result in the operation of the alternate and intermediate yarn guides, and the selection of groups of needles is shifted five needles in the opposite direction for the advance and return operations following the second pair of yarn guide selections which result in the operation of alternate and intermediate yarn guides. One such shift will have occurred previously to the operation indicated at 285.

In instances when all the yarn guides are operated pursuant to a single selection (as when the yarn guides pass between raised needles as indicated in Fig. 16), this shifting of the groups by one or more needles may occur every row. The shifting may also be such as to produce a diagonal fabric (i. e., shifting which is continuously in the same direction rather than reciprocal.)

Numerous other variations of selection of operation will be apparent to those skilled in the art.

As above indicated, moreover, the various yarn feeds and cams are removable and replaceable so that a wide variety of fabrics may be produced without any substantial modification in the machine.

In the form of machines of Figs. 11-16 there is provided means, which is especially desirable for use when yarn guides are swung about the fully advanced needles, to prevent the yarn from getting below the latches of the needles. As will be seen from Fig. 11, the yarn extending from the fabric to the yarn guide is considerably below the lowermost point of the latches when the needles are fully advanced. To assure that this yarn does not get beneath and behind the latches instead of being fed to the needles upon or above the latches, so as to be incorporated in the fabric, there are provided removably mounted units disposed at each point where a yarn guide is to be swung, and including a member extending inside the needles in such position and at such height that as the yarn is swung the yarn will extend over the member at a height such that it will be properly received by the needles. One such unit is shown in Figs. 12b and 14 and is

indicated generally by reference numeral 272. This includes a bracket 273 screwed onto the sinker cam ring 11b at a suitable point and carrying at its inner end an elongated arcuate strip 274 which passes inside the needles for a sufficient distance so that the yarn guide will complete its swing and the needles will be retracted by a retracting cam 49b while the member 274 is passing. A yarn from the fabric thus extends up over the member 274 and around the advanced needles and passes once more over the member 274 back to the yarn guide, as indicated in Fig. 14, so that the yarn is properly positioned on the needles. In order to further assist in maintaining the yarn in correct position during the swing of a yarn guide, there is also removably screwed on the sinker cam ring 11b a plate 275 having an arcuate edge extending outside the needles at the point where the yarn guide swings and having an upper surface at the same level as the upper surface of the arm 274. Preferably, and as shown, this upper surface is substantially aligned with or slightly below the pivot point of the latches of the needles when fully advanced. Units 272 are adapted to be disposed at points where the yarn guides will have imparted thereto a forward swing—i. e., a swing such that the yarn guide passes in front of the needles in the same direction as the main yarn feed moves.

Similar units may be used at points where the yarn guides swing in a reverse direction in certain instances; but, where a considerable number of needles are fully advanced, problems arise due to the fact that the advanced needle last passed by the yarn guide in its swing is the first to be retracted by the retracting cam, and consequently when the needles last retracted by the retracting cam are retracted the yarn extending from the yarn guide will have been firmly bound in the fabric so that there is no slack left for the formation of loops by the needles last retracted by the retracting cam. This difficulty applies in a large number of instances when means movable in one direction in front of fully advanced needles lays yarn against the same and retracting means thereafter retracts the advanced needles beginning with the advanced needle last passed by movable means and ending with the advanced needle first passed by movable means; and, as will be apparent, this feature of the invention is readily applicable to such situations. In order to overcome this difficulty, there is provided an arrangement which is incorporated in a unit indicated generally at 276 in Fig. 12a and disposed at a position where the yarn guides perform their reverse movement. This unit, as shown in Figs. 12a and 13, comprises a bracket 277 removably screwed on the sinker cam ring 11b and carrying an arm 278 having an upper surface at the same level as the upper surface of the arm 274 and of the plates 275. An additional one of said plates is, as will be seen, disposed outwardly of the arm 278. The arm 278, besides being positioned at a level such that it will serve the same purpose as the arm 274, is resiliently mounted so that the normal position of the part thereof past which the yarn guide swings will be a considerable distance inwardly of the needles, but so that the yarn, as the tension thereon increases due to the action of a retracting cam 49b, will yield and be drawn outwardly toward the needles, so that the slack provided as yarn is drawn over the arm during the swing of the yarn guide will

be taken up as needed for the formation of the loops by the latter ones of the needles which are retracted. This arm 278 may, in certain instances, be merely a resilient strip mounted on the bracket, but, as exemplified, it is a stiff strip pivotally mounted on the bracket by a removable bolt 279 and normally held outwardly by the pressure of a coil spring 280 carried in a bore in the bracket rearwardly of the pivot point of the arm and pressing inwardly against the arm 278. In order that the effective length of the arm 278 may be varied, it is provided with a series of holes 281 enabling the pivot point thereof to be shifted with respect to the bracket 277 by the removal of the bolt 279 and the shifting of the arm. It is to be observed, in addition, that the amount of inward swinging of the arm 278 under the pressure of the spring 280 is limited by the end 282 of a stem 283 on a screw 284 adjustably mounted in a bore in the bracket forwardly of the pivot point; thus enabling the amount of slack to be provided in any particular instance to be accurately regulated. As will be seen, when a yarn guide is swung during the passage of unit 276, the yarn from the yarn guide will extend about the arm 278 in the manner indicated at 285. Upon retraction of the needles, the increasing tension on the yarn as loops are formed will slowly draw the arm 278 outwardly toward the needles against the pressure of the spring 280 so that the slack originally provided will be available for the formation of the loops. The arm 278 thus serves as a means for providing slack as well as a means for insuring against the yarn getting below the latches of the needles, and may be employed for either or both purposes, as desired.

There are thus provided machines whereby wide varieties of design fabrics and other desirable types of fabric may be provided in a simple, expeditious, and effective manner and various difficulties in prior art structures overcome.

Since certain changes may be made in the above construction and different embodiments of the invention could be made without departing from the scope thereof, it is intended that all the matter contained in the above description or shown in the accompanying drawings shall be interpreted as illustrative and not in a limiting sense.

I claim:

1. In a knitting machine, in combination, a needle bed, a series of independent needles movably mounted thereon, a yarn guide swingable in at least a partial rotation thru an arc having a portion lying in front of the needles and extending therefrom to the rear of the needles at each side of said portion, the radius of said arc being at least as long as the distance between the far sides of a pair of needles, and means for moving said yarn guide through said arc for supplying yarn to certain of said needles, said moving means comprising a gear, a rack for operating said gear, and means for selectively operating said rack.

2. In a knitting machine, in combination, a needle bed, a series of independent needles movably mounted thereon, a yarn guide swingable in at least a partial rotation thru an arc having a portion lying in front of the needles and extending therefrom to the rear of the needles at each side of said portion, means to advance and retract desired ones of said needles, said arc having a radius of a length sufficient to encompass within said arc a portion of said bed on which a plurality of said needles are mounted, and said

arc lying in a plane so intercepting certain of said needles when the same are advanced that a movement of the yarn guide thru said arc will feed yarn to advanced needles, means to swing said yarn guide thru said arc in one direction between one set of advancing and retracting operations of said advancing-and-retracting means, and means to swing said yarn guide thru said arc in the opposite direction between another set of advancing and retracting operations of said advancing-and-retracting means.

3. In a knitting machine, in combination, a needle bed, a series of independent needles movably mounted thereon, a yarn guide swingable in at least a partial rotation thru an arc having a portion lying in front of the needles and extending therefrom to the rear of the needles at each side of said portion, and means to swing said yarn guide thru said arc first in one direction and then in the opposite direction.

4. In a knitting machine, in combination, a needle bed, a series of independent needles movably mounted thereon, a yarn guide swingable in at least a partial rotation thru an arc having a portion lying in front of the needles and extending therefrom to the rear of the needles at each side of said portion, and means to swing said yarn guide thru said arc twice in a single swinging movement thereof.

5. In a circular knitting machine, in combination, a needle cylinder, a series of needles thereon, a yarn guide mounted for rotative movement in an arcuate course which has a radius smaller than the radius of said needle cylinder and which twice crosses the line of said needles, means to move said yarn guide through said arcuate course in one direction and return it therethrough in the opposite direction, and means to manipulate certain of said needles to cause them to receive yarn from said yarn guide when so moved.

6. In a circular knitting machine, in combination, a needle cylinder, a series of needles thereon, a yarn guide mounted for rotative movement in an arcuate course which has a radius smaller than the radius of said needle cylinder and which twice crosses the line of said needles, means to adjustably mount said yarn guide to permit it to be adjusted to be swung thru other arcuate courses each having a different radius crossing the line of said needles twice, each of said radii being smaller than the radius of said needle cylinder and means to impart rotative movement to said yarn guide, through said arcuate course first in one direction and then in the opposite direction.

7. In a circular knitting machine, in combination, a needle cylinder, a series of needles thereon, a yarn guide mounted for rotative movement in an arcuate course which has a radius smaller than the radius of said needle cylinder and the axis of which is in a line which passes inside the line of needles near the top of the latter and which twice crosses the line of said needles, means to move said yarn guide through said arcuate course in one direction and return it therethrough in the opposite direction, and means to manipulate certain of said needles to cause them to receive yarn from said yarn guide when so moved.

8. In a circular knitting machine, in combination, a needle bed, a series of needles thereon, needle-operating means, said needle-operating means and said needle bed being mounted for relative movement, a second bed forming a unit with said needle bed in said relative movement, 75 yarn-guiding means mounted for rotative move-

ment in an arc which twice crosses the line of said needles for feeding yarn to certain of said needles, and means including elements mounted for radial sliding movement on said second bed to impart to said yarn-guiding means movement through said arc.

9. In a circular knitting machine, in combination, a needle bed, a series of needles thereon, needle-operating means, said needle-operating means and said needle bed being mounted for relative movement, a second bed forming a unit with said needle bed in said relative movement, yarn-guiding means mounted for rotative movement in an arc which twice crosses the line of said needles for feeding yarn to certain of said needles, means including elements mounted for radial sliding movement on said second bed to impart to said yarn-guiding means movement through said arc, and means to selectively operate said imparting means.

10. In a circular knitting machine, in combination, a needle bed, a series of needles thereon, needle-operating means, said needle-operating means and said needle bed being mounted for relative movement, a second bed forming a unit with said needle bed in said relative movement, yarn-guiding means mounted for rotative movement in an arc which twice crosses the line of said needles for feeding yarn to certain of said needles, means including elements mounted for radial sliding movement on said second bed to impart to said yarn-guiding means movement through said arc, and means to selectively operate said imparting means.

11. In a knitting machine, in combination, a needle bed, a series of needles on said bed, a yarn guide swingable across the line of said needles to feed yarn to certain of said needles, yarn guiding means for supplemental yarn located in proximity to the axis of swinging movement of said yarn guide, and means to cause said yarn guide to wrap its yarn around the yarn from said supplemental yarn-guiding means.

12. In a knitting machine, in combination, a needle bed, a series of independent needles movably mounted thereon, and a plurality of separate yarn guides each swingable independently of the others in at least a partial rotation through an arc having a portion lying in front of the needles and extending therefrom to the rear of the needles at each side of said portion, the arcs of swinging movement of adjacent yarn guides overlapping so that yarn from two of said yarn guides may be fed to certain of said needles.

13. In a knitting machine, in combination, a needle bed, needles on said bed, a yarn-feeding member swingable past needles on a portion of said bed to feed yarn thereto, a dial, an operating member mounted for radial sliding movement on said dial, means to selectively impart radial sliding movement to said operating member, and means to impart swinging movement to said yarn-feeding member in response to a radial sliding movement of said operating member.

14. In a knitting machine, in combination, a needle bed, needles on said bed, means to advance at least a plurality of the members of a group of said needles, means movable in one direction in front of the advanced needles to lay yarn against the same, means to thereafter retract the advanced needles beginning with the advanced needle last passed by said movable means and ending with the advanced needle first

passed by said movable means, and means arranged to provide slack in said yarn prior to the retraction of said advanced needles to permit said slack to be taken up during the retraction of said advanced needles whereby tendencies toward excessive tautness of the yarn during the retraction of the advanced needle or needles first passed by said movable means and last retracted will be avoided.

15. In a knitting machine, in combination, a needle bed, needles on said bed, a yarn guide swingable in at least a partial rotation through an arc having a portion lying forwardly of the line of said needles and extending to the rear of said needles at each side of said portion, resilient means arranged to extend rearwardly of said group of needles during the swinging of said yarn guide and to intercept said yarn and to provide slack therein, and means to advance certain of said needles for reception of yarn from said yarn guide and to retract said certain of said needles after said reception of yarn, said resilient means being yieldable during retraction of said certain of said needles to permit said slack to be taken up in order to prevent undesired tautness in the yarn during retraction of any of said certain of said needles.

16. In a knitting machine, in combination, a needle bed, needles on said bed, means to advance at least a plurality of the members of a group of said needles, a yarn guide swingable in at least a partial rotation through an arc having a portion lying forwardly of said group of needles and extending to the rear of the needles at each side of said portion, means to swing said yarn guide through said arc in one direction to feed yarn to the needles of said group advanced by said advancing means, means to retract the advanced needles of said group successively beginning with the last one in said direction and ending with the first one in said direction and means arranged to extend at the rear of the advanced needles during the swing of said yarn guide through said arc and acting to intercept yarn during the swing of said yarn guide and to provide slack therein and to permit said slack to be taken up during the operation of said retracting means on the needles of said group to prevent undesired tautness in the yarn during the operation of said retracting means with respect to the needles of said group.

17. In a knitting machine, in combination, a needle bed, a series of needles on said bed, needle advancing-and-retracting means, said bed and said advancing-and-retracting means being mounted for relative movement, means forming a unit with said bed in said relative movement and adapted to wrap a yarn around certain of said needles when advanced, and means forming a unit with said advancing-and-retracting means in said relative movement and extending during the operation of said wrapping means in proximity to said certain of said needles and in such position relative to the latches of the needles when the same are advanced to assure that the yarn from said wrapping means will not slip past the latches of the needles, said wrapping means being adapted in at least certain of its operations to swing around a plurality of advanced needles in a direction opposite to the direction of action of the advancing-and-retracting means in retracting the needles, and there being provided assuring means operative when the swinging of the wrapping means is in such opposite direction to provide slack in the wrapped

yarn and to permit said slack to be taken up during the retraction of the needles.

18. In a knitting machine, in combination, a needle bed, a series of independent needles movably mounted thereon, a yarn guide intermittently swingable in at least a partial rotation thru an arc having a portion lying in front of the needles and extending therefrom to the rear of the needles at each side of said portion, said arc having a radius of a length sufficient to encompass within said arc a portion of said bed on which a plurality of said needles are mounted, and means to selectively impart swinging movements to said yarn guide for supplying yarn to certain of said needles, said arc being substantially perpendicular to the line of said needles at the points where it crosses the same.

19. In a knitting machine, in combination, a needle bed, a series of independent needles movably mounted thereon, a plurality of separate yarn guides each swingable independently of the others in at least a partial rotation through an arc having a portion lying in front of the needles and extending therefrom to the rear of the needles at each side of said portion, said yarn guides being so spaced and said arms being so formed and disposed that the arcs of adjacent yarn guides overlap in front of the line of said needles sufficiently so that at least one needle will be included by both the arcs of adjacent yarn guides, and means to impart swinging movements to suitable ones of said yarn guides at desired periods in the operation of the machine for supplying yarn to at least certain of said needles.

20. In a knitting machine, in combination, a needle bed, a series of needles on said bed, a yarn carrier, said yarn carrier and said bed being mounted for relative rotative movement for supplying weft yarn to said needles, a yarn guide swingable across the line of said needles to perform a wrapping operation, and supplemental yarn-guiding means located in proximity to the axis of swinging movement of said yarn guide to pay out an additional yarn to be caught by at least certain of said wrapping movements.

21. A yarn guide for a knitting machine, said yarn guide having an opening in one end thereof, and having at least at a portion adjacent said end a relatively thick longitudinally extending central portion and at least one narrow longitudinal edge portion adapted to enter the space between two closely spaced knitting machine needles, and having a flaring portion between said edge and central portions to spread said needles, and being formed with means to guide yarn to said opening through a course longitudinal of said yarn guide within the confines of a thick part of said yarn guide from a point on said yarn guide remote from said end.

22. In a knitting machine, in combination, a needle bed, a series of needles on said bed, yarn-guiding means comprising a plurality of yarn-guiding elements each swingable on a common axis in at least a partial rotation thru an arc having a portion lying in front of the needles and extending therefrom to the rear of the needles at each side of said portion, and means for swinging each of said elements independently of the other thru said arc first in one direction and then in the opposite direction.

23. In a knitting machine, in combination, a needle bed, a series of needles on said bed, yarn-

guiding means comprising a plurality of yarn-guiding elements each swingable on a common axis in at least a partial rotation thru an arc having a portion lying in front of the needles and extending therefrom to the rear of the needles at each side of said portion, said elements being mounted on concentric shafts adapted for independent rotation one within the other, and means for rotating each of said shafts to swing said elements thru said arc first in one direction and then in the opposite direction.

24. In a knitting machine, in combination, a needle bed, a series of needles on said bed, yarn-guiding means comprising a plurality of yarn-guiding elements each swingable on a common axis in at least a partial rotation thru an arc having a portion lying in front of the needles and extending therefrom to the rear of the needles at each side of said portion, said elements being mounted on concentric shafts adapted for independent rotation one within the other, and means for rotating each of said shafts to swing said elements thru said arc first in one direction and then in the opposite direction, the innermost of said shafts having a passage therethrough to receive and guide yarn to said elements.

25. In a circular knitting machine having a needle bed, a series of latch-needles on said bed, needle advancing-and-retracting means, said bed and said advancing-and-retracting means being mounted for relative rotation, means forming a unit with said bed in said relative rotation for carrying yarn around certain of said needles when advanced, said yarn carrying means swinging in an arcuate path which twice crosses the line of needles and feeding the yarn in a plane below the hooks of the needles when the same are advanced, means forming a unit with said advancing-and-retracting means in said relative rotation and comprising a member extending behind the needles and having its upper surface positioned in a plane above the lowermost point of the latches of the needles when the same are fully advanced and of an extent sufficient to support the yarn between the two points where it crosses the line of needles whereby the yarn from said yarn carrying means is prevented from being wrapped about the needles below the latches thereof.

26. In a knitting machine, in combination, a needle bed, a series of independent needles movably mounted thereon, a yarn guide intermittently swingable in a circular path extending on both sides of said needle bed and lying in a plane substantially normal to the needles, the radius of said path being of a length to encompass a portion of said bed on which a plurality of needles are mounted, and means to selectively impart swinging movement to said yarn guide for supplying yarn to certain of said needles.

27. In a knitting machine, in combination, a needle bed, a series of independent needles movably mounted thereon, a yarn guide swingable in a circular path extending on both sides of said needle bed, the axis of rotation of said yarn guide being substantially parallel to and in line with said needles, the radius of said path being of a length to encompass a portion of said bed on which a plurality of needles are mounted, and means to impart swinging movement to said yarn guide for supplying yarn to certain of said needles.
